CLAIM

The ornamental design for a taco holder or the like, as shown and described.

DESCRIPTION

FIG. 1 is a top perspective view of a taco holder or the like, showing my new design;

FIG. 2 is an end elevational view thereof;

FIG. 3 is a side elevational view thereof; and

FIG. 4 is a bottom plan view thereof.

*Fig. 1**Fig. 2**Fig. 3**Fig. 4*
